UNITED STATES PATENT OFFICE.

ROBERT HOWARD WILLIAMS, OF MAIZE, KANSAS.

BRIDLE.

No. 851,463.

Specification of Letters Patent.

Patented April 23, 1907.

Application filed June 2, 1906. Serial No. 319,868.

To all whom it may concern:

Be it known that I, ROBERT HOWARD WILLIAMS, a citizen of the United States, and a resident of Maize, in the county of Sedgwick and State of Kansas, have invented a new and Improved Bridle, of which the following is a full, clear, and exact description.

This invention is an improvement in bridles, having for an object, among others, to provide a bridle which shall be of simple construction, humane, and an effective means to bring the horse to a quick stop. This last object is accomplished by making the check reins and driving reins as a continuous piece passing loosely through the bit and elbows at each side of the horse's head, thereby multiplying the power at the bit as applied to the reins and enabling the driver to control the horse with small exertion. The few parts employed in the bridle construction not only permits its manufacture at a small cost, but gives a decided neat appearance and obviates the use of heavy, cumbersome parts employed in many other bridles hitherto devised.

A further object is to so construct the bit used in connection with the bridle, with non frosting or poisoning metal, that it shall fit the horse's jaw below the grinders and above the nippers in such a way as not to press on the lip.

Reference is to be had to the accompanying drawings forming a part of this specification, in which similar characters of reference indicate corresponding parts in all the figures.

Figure 1 is a graphic representation of the fore part of a horse with my improved bridle applied; Fig. 2 is a plan view of the bridle with the parts in the same relation as when applied to the horse; Fig. 3 is a longitudinal section through a flanged elbow employed as a guide in connecting the several parts of the bridle together; and Fig. 4 is a transverse central section through the bit on substantially the line 4—4 of Fig. 2.

The numeral 1 indicates a back band having attached thereto a check rein hook 2 and guide rings 3 as is usual in the general harness construction. Adapted to be attached to the hook 2 is a loop 4, having fixed at each side thereof a check rein 5 passing through flanged elbows 6 down through eyes 7^a at the ends of a bit 7 and terminating in loops 8. To the loops 8 snap hooks 9 are engaged, which are attached to suitable reins by buckles 11, or in any other desired manner.

To the center of each flanged elbow 6 is connected a throat latch 12, made adjustable by a buckle 13, the connection being formed between the elbows and the throat latch by loops in the latch passing about the body of the elbows. Connected to the flanged elbows at each side of the throat latch in a similar manner, is respectively, a head strap 14 adjustable by a buckle 15, and a brow strap 16 adjustable by a buckle 17, the straps being made from a single piece of leather split to form them as shown in Fig. 3.

The bit 7 is made concavo-convex in cross section with rounded edges of a non-frosting and non-poisoning material, preferably wholly of aluminum or aluminum with a steel core 7^b and arched over at its center to fit the lower jaw of the horse below the grinders and above the nippers, in such a way as not to interfere or press on the animal's lips. The bit is also connected at each end through the eyes 7^a by a chin strap 18, made adjustable by a buckle 19 at an intermediate portion of the strap. In the practical construction of the bridle all of the elements will preferably be made of leather except the buckles, elbows and bit, the buckles and elbows to be of brass or other hard metal, and the bit to be of a composition as outlined.

In the operation of the bridle, when the reins are pulled on the bit is pressed on the horse's tongue, allowing the check rein 5 to freely slide through the elbows 6 and eyes 7^a of the bit, drawing the horse's head upward with multiple force. The horse is by this operation quickly controlled, as is evident. It is also apparent that with a slight pull on the reins, the horse's head is forced to stand erect through the action of the check rein, and the check rein in this particular performing the same function as in bridles of ordinary construction.

It is evident that various details of construction may be modified to some extent from that which I have employed in the embodiment of my invention as described; and I desire to have it understood that I consider that I am entitled to such changes as fall within the scope of the invention as claimed.

Having thus described my invention I claim as new and desire to secure by Letters Patent:

1. In a bridle, reins, a curved aluminum bit, a chin strap connected at each end thereof, flanged elbows, a brow strap and a head strap connected to the elbows, a throat

latch connected to the elbows intermediate the brow and head straps, check reins directly connected to the reins and freely slideable through the elbows and bit, and means 5 for adjusting all of said straps.

2. In a bridle, a bit, a chin strap connected at each end thereof, flanged elbows, a brow strap and a head strap connected to the elbows, a throat latch intermediate the brow 10 and head straps, and check reins directly con-

nected to the reins and freely slideable through the elbows and bit, for the purpose described.

In witness whereof I have signed my name to this specification in the presence of two subscribing witnesses.

ROBERT HOWARD WILLIAMS.
